UNITED STATES PATENT OFFICE.

NEILL RAY GRAHAM, OF NEW YORK, N. Y.

TYPE-WRITER.

No. 845,229.

Specification of Letters Patent.

Patented Feb. 26, 1907.

Application filed November 17, 1905. Serial No. 287,871.

To all whom it may concern:

Be it known that I, NEILL RAY GRAHAM, a citizen of the United States, residing in New York city, at 358 West Fifty-eighth street, in the county of New York and State of New York, have invented an Improvement for Type-Writers, (or machines for type-writing,) the title of which invention is "Sub-Super-Scriptor," and of which invention the following is a specification.

My invention relates to those type-writers (and machines for type-writing) which utilize the shift, (and shift-key,) (by "shift" I mean what is ordinarily understood as such in the type-writing terminology;) and the object of my invention is to give or supply a device for facilitating the writing (or type-writing) of—

I. *Subscripts*, (by "subscripts") I mean such characters as the 2 and 4 in H_2SO_4 , the 2 and 4 (subs) $C_2 + O_4 = 2CO_2$, and all similar or like figures, letters, or characters, and any figures, letters, or characters of a similar or like nature or position;—

II. *Superscripts*, (by "superscripts") I mean such characters as the 2 in $(x-y)^2$, the $n-1$ in $(x-y)^{n-1}$, the n in x^n , the 2 and 4 in H_2SO_4 , the # in *Scientific American*#—as when referring to foot-notes, &c.—and any figures, letters, or characters of a similar or like nature or position; and

III. Any *sub*—that is, any characters down from, below, or under the regular or straight line (or alinement) writing; *super*—that is, any characters up from, above, or over the regular or straight line (or alinement) writing; or any intermediate figures, letters, or characters.

This I accomplish by means of a device which rests upon or which may be connected to or with or joined directly to the shift-bar or shift of the machine, which device is held in working position by screws with shoulders or by a screw, (or by a pin or other suitable means of holding in position.) The device is provided in this particular instance with a notched slot, which slot travels upon the upper screw (or a screw or pin) as a guide. The notched slot allows the device to be moved into and hold a special position, and also to be moved up and down. The device is arranged so that the upper part is heavier than the lower part or so that it falls against the upper screw (or pin) as the shift is lowered. The special position of the shift had or obtained by the regulation of the notched

slot has a corresponding effect upon the carriage (and hence keyboard) of the machine, and thus permits of the direct writing of the subscripts, superscripts, any characters similar to or like those cited. (The position of the notch in the slot and the position of the slot may vary to suit the particular case where application is desired. The shape of the device may also vary as required, and the device may be connected directly to or with the shift-bar or shift.) This special position of the shift I attain through the mechanism of the device shown in the accompanying drawings, in which—

Figure 1 shows a front view of part of a type-writer with the new device in place as applied, for instance, to a machine in which the carriage-action happens to be up and down. This view shows the device as applied in one instance for the writing of subscripts. *a* is the shift, (and shift-key,) upon which shift-bar the new device in this instance rests and works. *b* shows the new device resting upon the shift-bar (or shift-key bar) and the notched slot at upper end. *c* is a screw provided with a shoulder, which screw regulates the travel of the device. *d* is a screw provided with shoulder to keep the device in this particular application from swinging out of position. (Where the device is connected or joined directly to the shift-bar, this screw would not be necessary.)

Fig. 2 is a part section taken on the plane of the broken line shown in Fig. 1 showing the shift and the new device as attached to the case-casting of the machine.

Fig. 3 shows the device apart, (as applied to this particular machine,) together with a holding-screw.

By slightly depressing the shift-key or shift-key bar *a* the device *b* falls until the screw *c* is in the notch provided in the slot. (The device is then in position for use.) By continuing the depression of the shift-key *a*—that is, by making a full shift—the device is lowered and travels upon the screw *c* to the end of the slot. Then by releasing the shift-key the device travels back the full length of the slot and the machine is ready for the regular or line writing. When subscripts and superscripts are not required, the device simply travels up and down the full length of the slot, following the shift and not interfering with the regular operation of the shift. This device can also be made to accomplish the same object in machines where the car-

riage-action is different from that shown. The device may also be connected directly to or with the shift, (in which case it might work on a pivot or other suitable working piece.)

5 I claim—

1. In a type-writing machine, the combination of a shift-key, a locking-plate provided with a slot, a notch in one edge of said slot and adapted to coöperate with a stop on the machine-frame, substantially as described.

2. In a type-writing machine, the combination of a shift-key, a locking-plate having a notch, a positive stop adapted to coöperate with said notch to arrest said shift-key at a predetermined point intermediate its shifting movement, substantially as described. 15

NEILL RAY GRAHAM.
